UNITED STATES PATENT OFFICE.

GEORGE W. EUKER, OF PITTSFIELD, MASSACHUSETTS, ASSIGNEE TO CORINNE M. SANCHE, OF NEW YORK, N. Y.

ELECTROTHERAPEUTIC APPARATUS.

1,206,784.

specification of Letters Patent. Patented Nov. 28, 1916.

Application filed July 18, 1912. Serial No. 779,792.

To all whom it may concern:

Be it known that I, GEORGE W. EUKER, a citizen of the United States, residing at Pittsfield, in the county of Berkshire and State of Massachusetts, have invented certain new and useful Improvements in Electrotherapeutic Apparatus, of which the following is a specification.

The invention relates to electro-therapeutic apparatus for the treatment of certain diseases, being designed especially to increase the circulation of the blood by electrically massaging the affected parts; and it consists in regulating the frequency of operation and intensity of the electrical impulses, from a battery or other suitable electrical supply circuit, by means of a rheostat or voltage-regulator, said impulses being provided by interrupting an electric circuit, and discharging the same into the rheostat or voltage-regulator and then into an electrode provided with a plurality of metal contacts in electrical connection with positive and negative currents.

25 In the drawings—Figure 1 is a diagrammatic view of my electrical-massage apparatus; Fig. 2 is a central, longitudinal section of the induction-coil, circuit-breaker, and frequency-regulator; Fig. 3 is a plan view of the case, with lid open, showing the arrangement of various parts of the apparatus, and Fig. 4 is an edge view of the electrode.

Referring to the several views, the numeral 1 indicates a suitable case or box provided with a hinged lid or top 2. The case is preferably divided into three compartments, one of which contains a suitable source of electrical supply, such as a battery 3, another the induction-coil 4, the battery-switch 5, and the frequency-regulator 6 and rheostat 7, and the remaining one containing the cable reel 8, and the electrode 9, when not in use.

45 The induction coil 4 is supported in a yoke 10 of closed magnetic circuit, and is provided with an oscillatory armature 11 mounted on a steel shaft 12 which extends some distance into the iron core of the coil. Also mounted on the shaft 12 is an arm 13 adapted to break the circuit between the two contacts 14 and 15; contact 14 being in electrical connection with contact 16 of the rheostat by conductor 17, and with the induction-coil by conductor 18 through the coil-wind-

ing and to switch-contact 5'; while contact 15, which is a flat spring provided with a platinum contact-point 15', is in electrical connection with the condenser 19 by conductor 20, and with the battery by conductor 22, thus completing the battery circuit when switch 5, which is connected to battery by conductor 22, is in engagement with switch-contact 5'. The moment this circuit is completed, the magnetic force in yoke 10 and the core of the induction-coil pulls armature 11 to a position parallel with said yoke. However, before this position of the armature is attained, the circuit-breaker 13, which is at a certain fixed adjustment on its shaft, engages spring-contact 15 and forces it away from contact 14, thus breaking the contact and interrupting the battery circuit. The armature is then returned to a position fixed by an arm 23 which is attached to a knob 24 of the frequency-regulator, by means of a balancer 25 mounted on shaft 12 and moving with the same; the balls of the balancer being so adjusted on their rod as to place the armature out of balance, so that it will be automatically returned to normal position. By turning knob 24 the arm 23 is made to engage the armature and moves it toward the yoke 10. The moment the circuit is completed the magnetic force pulls the armature 11 to a parallel position with the yoke 10. Before however, this position is attained, the circuit breaker 13, which is mounted on the shaft 12, and moves with it and the armature 11, at a certain predetermined adjustment, engages the lower contact 15, which, as stated, is a flat spring with a platinum point contact, and bends it down or off from the upper contact 14, thus interrupting the battery circuit. The armature 11 is then brought back to a position fixed by the arm 23, by means of the balancer 25. This latter element consists of a short shaft with two balls carried by the shaft 12 and moves with it, and is so adjusted as to put the armature out of balance so that it will return to its normal position without the aid of springs.

The arm 23 is attached to a knob 24, and by turning the latter the arm 23 is moved into engagement with the armature, and shifts the latter toward the yoke 10, thus shortening the stroke which produces faster interruptions of the battery circuit by separating the contacts 14 and 15. The dotted

circles 50 and 51 are employed to indicate two of many of the adjustments of the armature.

- Conductor 20 continues from condenser 19 to contact 26 of the rheostat, which contact is connected with a resistance wire 27 which loops in and connects with all of the contacts on the rheostat, thus giving a total of 78 ohms of six ohms per step, more or less as may be required. Contact 26 is connected with binding-screw 28 by conductor 29, over which the current passes to bracket 30; through bracket 30 and short shaft 31 to binding-screw 32 to which one wire 33 of the cable 34 is connected. The current passes over wire 33 to a number of metal contacts 35 connected in series and fixed upon the insulated surface of the electrode 9. The other wire 36 of the cable 34 is connected with a number of metal contacts 37, also in series on the insulated surface of the electrode, and with a binding-screw 38, from which the current passes to a short shaft 39; thence to a bracket 40 and binding-screw 41; thence to rheostat, over conductor 42, the rheostat being at rest on contact 16; thence by way of conductor 18 to binding-screw 43 and thence through the coil to binding-screw 44. The current also passes from contact 16, over conductor 17 to contact 14. The electrode is provided with a mat 9' of suitable absorbent material held in place by a ring 9".
- Mounted on the short shafts 31 and 39, journaled in the brackets 30 and 40 respectively, and suitably insulated therefrom, is a reel upon which the cable, which passes through the brass tubular handle 45 of the electrode, is wound and unwound. The reel may be of any approved construction, preferably of a window-shade roller type, with spring for winding up the cable and pawl and ratchet stop arrangements; the cable passing through the tubular handle is insulated therefrom by a bushing 46.
- The rheostat being on contact 16, the full current from the coil will be discharged into the contacts 35 and 37, which are so distributed over the insulated surface of the electrode that when the absorbent mat is placed upon them, the current will be evenly distributed into said mat, thoroughly charging the same, so that when the mat is pressed against the affected part of the body, the exact electrical impulse will be felt as produced by the armature movement, slow or fast (low or high) frequency, according to the adjustment of knob 24, the frequency regulator being provided with indicating marks of 100 and 1000, and a pointer 47. But when the switch-arm of the rheostat is moved over the contact-points thereof to-

ward the contact 26 the voltage at the contacts 35 and 37 will be gradually reduced, and when the switch-arm finally reaches contact 26, the voltage will be zero, as the switch arm then short-circuits conductors 29 and 42 leading to contacts 35 and 37.

It will be obvious, from the construction of the electrode, that only that part of the body in contact with the covered surface of the electrode, and within zone of electrical discharge, will be subjected to treatment, so that it is possible to massage or treat only the afflicted part of the body.

Having thus described my invention, what I claim is:

1. An electrical apparatus comprising positive and negative electrodes, a suitable source of electrical supply, a single field coil winding, an oscillatory armature supported in a closed magnetic circuit, means for regulating the electrical impulses in frequency of operation, and means for regulating the intensity of the electrical impulses.

2. An electric apparatus comprising positive and negative electrodes; a suitable source of electrical supply, a single, field-coil winding; an oscillatory motor in a closed-magnetic yoke, and a rheostat for regulating the intensity of the electrical impulses.

3. An electric apparatus comprising positive and negative electrodes; a suitable battery or other electrical supply, a single, field-coil winding; an oscillatory motor in a closed magnetic yoke; a current interrupter, and a voltage-switch for regulating the intensity of the electrical impulses, and a frequency switch for regulating the operations of impulses.

4. An electric apparatus comprising positive and negative electrodes; a suitable source of electric supply and condenser; an induction-coil supported in a yoke of closed magnetic circuit; an oscillatory armature; means for normally holding said armature, a current interrupter, and a voltage and frequency regulator.

5. An electric apparatus comprising positive and negative electrodes; a suitable battery; or supply of electricity, an induction-coil supported in a yoke of closed magnetic circuit, an oscillatory armature; means for normally holding said armature; means for regulating the movement of the armature; a current-interrupter, a voltage-regulator, and condenser.

In testimony whereof I affix my signature in presence of two witnesses.

GEORGE W. EUKER.
